Primary Examiner — Charles D Hanson(74) *Attorney, Agent, or Firm* — Panasonic IP Management; Kerry S. Culpepper(57) **CLAIM**

We claim the ornamental design for a fender for electric wheelchair, as shown and described.

DESCRIPTION

FIG. 1 is a front perspective view of a fender for electric wheelchair of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is an end view of the sectioned part taken along the line 8-8 in FIG. 2 with the internal parts being omitted.

The broken lines in the drawings represent portions of the fender for electric wheelchair that form no part of the claimed design.
